(57) **CLAIM**

The ornamental design for an ampoule, as shown and described.

DESCRIPTION

FIG. 1 is a perspective view of the ampoule.

FIG. 2 is a front view thereof.

FIG. 3 is a rear view thereof.

FIG. 4 is a bottom view thereof.

FIG. 5 is a top view thereof.

FIG. 6 is a side view thereof; and,

FIG. 7 is an opposite side view thereof.

The broken lines are included for the purpose of illustrating unclaimed portions of the ampoule and form no part of the claimed design.

1 Claim, 6 Drawing Sheets

FIG. 1

FIG. 2

FIG. 3

FIG. 4

FIG. 5

FIG. 6

FIG. 7
